United States Patent Office.

JOSEPH H. SPRINGER, OF PHILADELPHIA, PENNSYLVANIA.

Letters Patent No. 74,442, dated February 11, 1863.

IMPROVEMENT IN HIGH AND LOW-WATER ALARMS FOR STEAM-GENERATORS.

The Schedule referred to in these Letters Patent and making part of the same.

TO ALL WHOM IT MAY CONCERN:

Be it known that I, JOSEPH H. SPRINGER, of Philadelphia, in the county of Philadelphia, and State of Pennsylvania, have invented certain new and useful Improvements in Automatic Indicators for Steam-Boilers; and I do hereby declare that the following is a full, clear, and exact description thereof, reference being had to the accompanying drawings, and to the letters of reference marked thereon, which form a part of this specification, in which—

Figure 1 is a longitudinal vertical section, taken through the line *x*, and

Figure 2 a side elevation, exhibiting the glass gauge, also the cocks, by means of which the cylinder is connected with the steam-generator.

The nature of my invention consists, first, in the employment of weights, suspended in a cylinder, for the purpose of giving an alarm, in case of high or low water, or over-pressure of steam, substantially in the manner hereinafter set forth; second, in the use of a hollow cap as a receptacle for the safety-valve.

To enable others skilled in the art to make and use my invention, I will now describe its construction and operation.

A represents a double cylinder, provided at its top and bottom with rims *b b*. To these rims are secured the plates *e e'*, which should fit tight and accurately over the rims *b b*. On the under side of plate *e* are the hangers *a a'*. *g* represents a cam-lever, pivoted at its centre to hanger *a*. *g'* is a supplementary lever, with a friction-roller at one end resting upon the cam-lever, while its opposite end is pivoted to hanger *a'*. Through the plate *e* is an orifice, in which is placed the valve *i*. The lower end of this valve rests upon the supplementary lever, as seen in fig. 1. *B B* represent two weights, which may be of stone, or any other suitable material, and which are suspended from the ends of lever *g* by cords or wire of unequal length. I would observe that one of these weights should be greater by one-third than the other, *i. e.*, in weight. The object of this is that the large stone or weight, when immersed in water, weighs less by one-third, or, more properly speaking, displaces one-third of its weight, so that the smaller weight will balance the larger. This feature of the invention will be fully understood hereafter. *h* represents the valve-lever, provided with the movable weight *n*. Said lever is pivoted to the upright *e* on plate *e*, and rests upon the valve *i*, as shown in fig. 1. *D* is a hollow cap, fitting upon and secured to plate *e*. Upon the top of this cap is the whistle *E*. *G* represents the glass gauge, connected to the cylinder at top and bottom by means of tubes *o o*. The object of this gauge is to indicate the cause of the alarm. *H H* are two cocks, which connect the cylinder to the boiler; one, half way above the water-line, and the other the same distance below it.

The operation of my invention is as follows: The safety-valve is first weighted to the pressure the boiler is to carry, say sixty pounds. Now let the water in the machine until it submerges the large stone, when the small one will balance it. If the water in the boiler should fall to near the bottom of the large stone, the difference in the weight, operating on the cam-lever and the supplementary lever, will raise the safety-valve, and admit the steam to the whistle. If water be again pumped into the boiler, and raised high enough to submerge both stones or weights, the gravity of the weights becomes relatively what it would be if both were out of the water, again raising the valve and giving the alarm. Thus, it will be observed that my invention will indicate high steam, and also high and low water; the cause being told by looking at the glass gauge.

What I desire to secure by Letters Patent, is—

1. The employment of two unequal weights, suspended by cords or rods of unequal lengths to a lever, with its fulcrum at its centre, arranged inside of a cylinder attached to the outside of a steam-boiler, said weights being subject to the action of high and low water, substantially as and for the purpose set forth.
2. In combination with the above, the levers *g g'*, arranged within a cylinder outside of the boiler, substantially as and for the purpose specified.
3. Arranging the safety-valve within the hollow cap *D*, substantially as and for the purpose specified.
4. The glass gauge *G*, when used in combination with cylinder *A*, and weights *B B*, substantially as set forth.

In testimony that I claim the foregoing as my own, I affix my signature in presence of two witnesses.

JOSEPH H. SPRINGER.
